UNITED STATES PATENT OFFICE.

FRANK S. BARKS, OF ST. LOUIS, MISSOURI, ASSIGNOR TO LINCOLN STEEL AND FORGE COMPANY, OF ST. LOUIS, MISSOURI, A CORPORATION OF MISSOURI.

MINE-CAR COUPLER.

Application filed June 10, 1921. Serial No. 476,445.

To all whom it may concern:

Be it known that I, FRANK S. BARKS, a citizen of the United States, residing at St. Louis, Missouri, have invented a certain new and useful Improvement in Mine-Car Couplers, of which the following is a full, clear, and exact description, such as will enable others skilled in the art to which it appertains to make and use the same, reference being had to the accompanying drawings, forming part of this application, in which—

Figure 1 is a top plan view partly in section of my improved mine car coupler.

Figure 2 is a vertical sectional view of the parts shown in Figure 1.

Figure 3 is a detail view of the link centering spring.

This invention relates to a new and useful improvement in mine car couplers, the object being to provide a construction which may be employed with an ordinary pin lifting device such as commonly employed on standard gauge railroads whereby it is unnecessary for a person to enter between the cars to effect a coupling thereof, such as is now commonly done in mine cars.

Another object of my invention is to construct the coupler heads and link in such a manner that the cars can be hauled on tracks having curves of a relatively short radius without derailing the cars. This has heretofore been accomplished by using a plurality of links for coupling the cars, but in service these links frequently drag on the ground and become caked with mud and dirt, which, drying thereon, makes them difficult to handle.

Another object of my invention in using a single coupling link is to enable the cars to be automatically coupled together on a curve.

Further objects are to provide means for yieldingly centering the link and yieldingly mounting the link in a horizontal position, this yielding characteristic of the link permitting vertical movement between the faces of the coupling-buffer heads without seriously affecting the operative relation between the parts.

In the drawings, I have shown a link carrying coupler head which may be provided with a draw-bar cooperating with draft springs which will yield under buffing and hauling strains; but these are not shown, as they form no part of my present invention. I may say that the companion coupler head may be similarly mounted. Coupler head 1 has flaring sides and converging centering back walls 2. The forward edges of the horizontally disposed top and bottom walls which constitute the jaws of the coupler being provided with upwardly and downwardly extending vertical flanges 4, which provide a bearing face for co-operation with similar flanges on the companion coupler.

5 indicates a strengthening rib medially arranged on the top wall of the coupler 1 which is enlarged at its forward end to form a boss having a vertical cylindrical opening 6 for receiving the cylindrical shank of a permanently mounted coupler pin 7. This pin is provided with the usual head portion 8 above which extends a pair of lugs 9 forming a bifurcation in which is loosely arranged the free end of a coiled torsional spring 10, the opposite end of which spring is secured to the rib 5 by means of a bolt 11. As shown in Figure 3, the free end of spring 10 is preferably refolded upon itself as at 10^a to form an extended bearing to co-operate with lugs 9.

7^a indicates a rectangular shank portion of coupler pin 7, below which is a cylindrical portion 7^b reduced and threaded at its lower end as at 7^c to receive a nut 12, which nut bears against a spring 13 arranged therebetween and the lower face of the coupler head. 14 indicates a link having an elongated rectangular slot 14^a in its attached end and through which the squared shank portion 7^a of the coupler pin 7 passes. This slot permits the link 14 to slide longitudinally on the coupler pin, and when the rear end of the link strikes the converging back walls 2, said walls will tend to center the link. I, however, prefer to rely upon spring 10 for centering purposes. This

spring tends to maintain the coupler pin 7 in a position in which the refolded free end is radially disposed relative to the securing bolt 11 and as the coupling pin is free to 5 rotate in the coupler head, it will be obvious that through its squared shank portion 7^a engaging the walls of a rectangular slot 14^a in the link 14, said link will be maintained in a central position. By virtue of 10 the shoulder 7^d between the cylindrical body portion of the coupler pin and the squared shank 7^a thereof bearing upon link 14, said link will be normally held against the inner face of the lower coupler jaw due to the 15 downward pressure exerted on the upper end of the coupler pin by the torsional spring 10. This spring 10 may be said to perform the dual functions of centering the coupler pin 7 and link 14 and yieldingly holding said link in a horizontal position. 20 However, spring 13 may be employed to assist spring 10 in yieldingly holding link 14 in a horizontal position; but spring 13 may be dispensed with, if desired.

25 The rectangular slot 14^a of the link is closed by a cross member 14^b beyond which the members of the link diverge, as at 14^c, and are connected by an end member 14^d whose inner face is arcuate while its outer edge is chamfered and formed with converging rounded bearing faces 14^e which are designed to co-operate with the converging back wall 15 of the companion coupler 16.

30 17 indicates a liftable coupling pin of ordinary construction designed to pass through the opening in the outer end of the link and to engage the walls of registering cylindrical openings in the top and bottom jaws of a coupler head 16. In operation, lifting means 35 may be provided to co-operate with the liftable coupling pin 17, but these form no part of my present invention.

In operation the mine cars are preferably 40 equipped with my couplers in such a manner that there will be a coupler head with a connected link at one end of the car and a female coupler head at the other end of the car. The cars are preferably arranged on the track in such a way that the attached link 45 in a coupler of one car will be received by the female coupler head of an adjacent car. The coupler heads being mounted on the cars, the spring 10 tends to yieldingly hold the link in a central as well as a horizontal position, the latter being supplementally maintained by the spring 13. The elongated rectangular slot in the link permits the link to move inwardly and outwardly, or to be held in position either well within, or projecting a considerable distance from, the coupler head. 55 To this extent the link may be said to be floating.

When the cars are to be coupled together, the entering outer edge of the link will ordinarily guide the link between the jaws

of the female coupler head, the chamfered edges compensating for ordinary irregularities in the heights of the coupler heads from the track. When the link enters the female coupler head and the liftable pin is cocked in 70 position, as is the usual practice, the shock of coupling the cars together is usually sufficient to cause the pin to drop into coupling position. Should the link engage the converging walls 15, said walls will tend to center the link, if the coupling occurs on a straight track and the link stands slightly displaced to one side. If the coupling is effected on a curved track, then the converging walls 15 tend to move the link laterally, 75 but the arcuate shape of the end member of the link and the play between the inner face of said end member and the coupling pin 17 is such that ordinarily the pin will drop into position in the fan shaped opening 80 of the link irrespective of whether or not the link stands in the central position or is slightly displaced to one side thereof. The side walls of the coupler jaws are cut away so that the link is free to swing laterally 85 when the cars are being moved from a track having a curve of relatively short radius. The vertical faces of the coupler heads when in contact with each other form extending 90 bearings to take care of the buffing stresses, and these faces are sufficiently projected beyond the transverse plane of the end of the car body that they will prevent the corners of the car bodies from striking each other on short curves.

95 The coupler heads are preferably made of steel castings and the link may be a forging but the material of which the parts are composed and the proportions of the parts will readily suggest themselves to those skilled in the art.

100 What I claim is:

1. The combination with a coupler having spaced horizontal jaws, of a pin swiveled in said jaws, a link mounted between the jaws and upon said pin, said link having sliding movement relative to said pin and having vertical movement with said pin relative to said jaws but being designed to turn with the pin, and a spring engaging the upper end of the pin for maintaining the links in predetermined vertical and horizontal planes.

110 2. In a car coupler, the combination of horizontally disposed jaws spaced from each other, a pin swiveled in said jaws, a link between the jaws and mounted on said pin, said pin having a bifurcated upper end and a coiled spring fixedly attached at one end to the coupler and having its free end engaging in the bifurcation of said pin and adapted to be distorted by either angular or upward movement of said pin.

120 3. In a coupler, the combination of horizontally disposed jaws, a link slidingly mounted between said jaws, means for yield-

ingly maintaining said link in a central horizontally disposed position, said link having a fan shaped opening in its outer end.

4. The combination of a coupler having upper and lower horizontally disposed jaws, a pin pivoted in said jaws, a link mounted for rotation with said pin and supported on the upper face of said lower jaw, a down-

wardly facing shoulder on said pin engaging said link, and a spring thrusting said pin 10 downwardly to hold said link in horizontal position.

In testimony whereof I hereunto affix my signature this 6th day of June, 1921.

FRANK S. BARKS.
